UNITED STATES PATENT OFFICE.

LAWSON J. STUKEY, OF PITTSBURG, KANSAS.

WASHING-MACHINE.

1,400,388.

Specification of Letters Patent. Patented Dec. 13, 1921.

Application filed May 17, 1921. Serial No. 470,273.

To all whom it may concern:

Be it known that I, LAWSON J. STUKEY, a citizen of the United States, residing at Pittsburg, in the county of Crawford and State of Kansas, have invented certain new and useful Improvements in Washing-Machines; and I do hereby declare the following to be a full, clear, and exact description of the invention, such as will enable others skilled in the art to which it appertains to make and use the same.

The present invention relates to a washing machine, and aims to provide a novel and improved laundry appliance of that character for efficiently washing clothes, fabrics, and the like.

Another object of the invention is the provision of a washing machine having a basket adapted to be reciprocated within the tub or casing for thoroughly agitating the clothes and water to obtain an efficient cleaning action.

A further object is the provision of a novel basket of that kind for holding the clothes and agitating the water through them.

A still further object is the provision of novel actuating means for reciprocating the basket.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a plan view of the machine, with the cover removed.

Fig. 2 is a side elevation thereof.

Fig. 3 is a vertical section on the line 3—3 of Fig. 4, portions being shown in elevation and the top of the basket being removed.

Fig. 4 is a section on the line 4—4 of Fig. 3, portions being broken away.

A rectangular tub or casing 7 is provided of suitable size, which is preferably supported on legs 8, and opposite handle bars 9 are secured to opposite walls of the tub at the rim thereof, and have handles 10 projecting beyond the other side walls for convenience in lifting or carrying the tub. A cover 11 is fitted on the rim of the tub to

prevent water from splashing therefrom when the machine is in operation.

Disposed for vertical reciprocatory motion in the tub is a clothes basket 12 comprising a suitable frame 13 and wire mesh or screen side walls 14 having large openings for the ready passage of water therethrough. The bottom of the basket is composed of a set of parallel slats or bars 15 which are inclined transversely thereof, to form water deflectors. Said slats or deflectors 15 are spaced apart to provide slots between them for the upward and downward passage of water therethrough, and the slats of the two halves are inclined reversely, as seen in Fig. 4.

The basket has a top or closure 16 fitted therein and composed of a suitable frame 16 and a wire mesh or screen panel 18 secured to the frame. This top 16 is adjustable in the basket, for holding the clothes within the basket for vertical motion therewith. When the basket is full of clothes, the top will be disposed adjacent to the rim of the basket, whereas when the basket is only partially filled, the top is pressed down until the clothes, when dry, support the top thereon. Vertical top-supporting bars 19 are secured to opposite walls of the basket on the interior thereof, and the top 16 has latches 20 engageable in apertures 21 provided in said bars, whereby the top can be secured in different vertical positions, each of said bars having a series of such apertures, as seen in Figs. 3 and 4. By adjusting the top in the basket according to the amount of clothes therein, the clothes are confined to the bottom portion of the basket, although they can be loose between the bottom and top, thereby avoiding the undesirable relative vertical motion of the clothes and basket with respect to one another beyond a slight amount to permit of the agitation of the clothes.

The basket is guided for vertical movement in the tub by means of channeled or grooved shoes 22 secured to opposite sides of the basket on the exterior thereof and engaging vertical rails 23 secured to opposite side walls of the tub on the interior thereof.

In order to move the basket up and down, a crank shaft 24 is journaled in bearings 25 secured to opposite walls of the tub 7 near the upper edges thereof, and said shaft has cranks 26 adjacent to said walls and con-

5 nected by pitmen or links 27 with the bottom portion of the frame 18, so that the rotation of the shaft will impart vertical reciprocatory motion to the basket. A fly and balance wheel 28 is secured to one projecting terminal of shaft 24, and has a weight 29 at that side of the shaft opposite to the cranks 26, for balancing the mechanism. The weight 29 substantially balances the 10 basket and clothes therein, whereby the mechanism will operate easily and smoothly.

A pinion 30 is secured to the other projecting terminal of the shaft 24 at that side of the tub opposite to the balance wheel 28, 15 and is disposed within and meshes with an internal gear wheel 31 which is mounted for rotation, as at 32, from the corresponding side wall of the tub. The wheel 31 has a crank handle 33 for conveniently rotating it 20 by hand, although it can serve as a pulley wheel when it is desired to operate the machine by an electric motor or the like. The rotation of the wheel 31 will impart a higher speed of rotation to the crank shaft 24, whereby to reciprocate the clothes basket at a comparatively high speed. 25

In using the machine, when the cover 11 is removed, and the latches 20 disengaged from the bars 19 and the top 16 of the basket removed, the clothes can be readily placed in the basket. The top 16 is then replaced within the basket and is permitted to settle on the clothes, and the latches are then engaged with the respective apertures 30 21 of the bars 19, thereby fastening the top in the basket. The water and soap are then put in the tub, and the cover 11 applied. By rotating the wheel 31, the crank shaft 35 will reciprocate the basket up and down 40 with a fast motion, and the clothes are carried up and down with the basket, thereby agitating the water and clothes for clean-

ing the clothes. The basket having its side walls, top and bottom foraminous will permit the water to pass through easily, so as 45 to pass through the clothes. Furthermore, the deflecting slats 15 will cause the agitation of the water, inasmuch as said slats will deflect the water toward and away from the center of the basket as the basket moves 50 downwardly and upwardly, respectively. This will not only agitate the water, but also agitate and stir up the clothes in the basket. After the machine has been run a sufficient time to clean the clothes, they are 55 readily removed when the cover 11 and basket top 16 are removed.

Having thus described the invention, what is claimed as new is:—

1. A washing machine comprising a tub, 60 and a clothes basket mounted for reciprocation in said tub and having a set of transversely-inclined slats for deflecting the water during the reciprocation of the basket for agitating the water and clothes within 65 the basket.

2. A washing machine comprising a tub, and a basket mounted in the tub for vertical reciprocation and having slats at the bottom thereof, some of the slats being inclined transversely in one direction and the other slats being inclined transversely in another direction for deflecting the water during the reciprocation of the basket and agitating the water and clothes within said 75 basket.

In testimony whereof I have signed my name to this specification in the presence of two subscribing witnesses.

LAWSON J. STUKEY.
